(57) **CLAIM**

The ornamental design for an package for orally dillutable medication, as shown and described.

DESCRIPTION

FIG. 1 is a front elevational view of an orally dillutable medication-delivery strip and associated carrying case showing my new design;

FIG. 2 is a rear elevational view thereof;

FIG. 3 is a side elevational view thereof;

FIG. 4 is a top plan view thereof;

FIG. 5 is a bottom plan view thereof; and,

FIG. 6 is a perspective view thereof.

The broken line showing of environment in FIGS. 1 and 6 is for illustrative purposes only and forms no part of the claimed design.
